UNITED STATES PATENT OFFICE.

WILLIAM H. CHAPMAN, OF MONTCLAIR, NEW JERSEY, ASSIGNOR TO GENERAL MOTORS CORPORATION, OF DETROIT, MICHIGAN, A CORPORATION OF DELAWARE.

WORK HOLDEE.

Application filed June 6, 1924. Serial No. 718,313.

This invention relates to work holders and is herein shown as embodied in apparatus for holding hollow sleeves and the like for grinding.

In the manufacture of sleeves or rings, one practice is to support the sleeves on an arbor between head and tail stocks which rotate the work during the operation of a tool. It is advantageous to work simultaneously on a number of sleeves held in axial alignment but it is a very fatiguing operation for an operator to hold the heavy arbor and its sleeves while bringing the tail stock to supporting and centering position. The operation of removing the work pieces and substituting others has hitherto been slow and unsatisfactory.

An object of the invention therefore is to provide a work holder which will relieve the operator of the necessity of supporting heavy weights when inserting the work pieces in the machine. Another object is to provide a work holder by means of which the greater part of the delay incident to changing work pieces can be overcome.

To these ends and also to improve generally upon devices of the character indicated my invention consists in the various matters hereinafter described and claimed.

Referring to the drawings, Figure 1 is a vertical longitudinal section through the left hand portion of the apparatus.

Figure 2 is a vertical longitudinal section through the right hand portion of the apparatus, the draw rod being shown in an opposite extreme position from the position shown in Figure 1.

Figure 3 is a perspective view of the quick detachable holder or clamping member.

Figure 4 is a left hand end elevation showing the rod operating mechanism.

Figure 5 is a front elevation of a portion of the rod operating mechanism of Figure 4.

Figure 6 is a vertical longitudinal section through the intermediate portion of the apparatus and

Figure 7 is a section on the line 7-7 of Figure 6.

G indicates a tool, herein shown as a wide grinding wheel, adapted to operate on a number of work pieces W, herein shown as hollow sleeves. The wheel is mounted to engage the rear outer surface of the work pieces for external grinding and is preferably given a slight axial reciprocation to

insure even wear. The work pieces W are in axial alignment and are clamped against one another and against a shoulder 10 on a bushing 12 which is supported and driven by a hollow spindle or arbor 14. The bushing has driving lugs 16 projecting from the shoulder and engaging driving pins 18 slidably mounted in a head 20 integral with the spindle. The spindle has one portion surrounding and spaced from an axially movable rod 22 and another portion splined to the rod by a key 24 slidable in a slot of the spindle. A quick detachable clamping member or holder 26 abuts against the endmost work piece W and clamps all of the work pieces against each other and against the shoulder 10. The member 26 is substantially U-shaped and comprises a disc having a slot 28 to straddle the rod 22 and a rear spherical face 30 cooperating with a corresponding face on a nut or limit member 32 threaded on the rod. The spherical faces allow the member 26 to align itself and bear uniformly against the endmost work piece. The nut 32 is secured by a locking nut 34, and so the clamping member 26 has a finger piece 36 spaced from the nuts so that it can be lifted from the rod 22 to release the work when the rod and the nuts are moved to the right. The nuts are of smaller diameter than the bushing so that the latter can be slid off endwise. The head 20 has a recess receiving a cross pin 38 passing through the shaft and aligned with the ends of the driving pins 18 which also serve as knock-off pins to loosen the bushing from the spindle. Upon sliding the rod 22 to the right, the clamping member 26 can be lifted and the loosened bushing and the work pieces can be removed by axial movement. Then a second bushing, previously loaded with work pieces, can be slid onto the spindle and clamped in position by applying the member 26 and sliding the rod 22 to the left by mechanism which will be hereinafter described.

The head 20 is fastened by screws to a collar 40 threaded on the end of a hollow driven sleeve 42 supported in plain half bearings 44 and 46 in a casing 48 which is slidable in ways on the machine frame. The half bearings are arranged downwardly and towards the front and the half bearing 44 is enclosed at the top and rear by a bearing cap 50 having a radial recess slidably sup-

porting a bearing block 52 which conforms to the outer surface of the driven sleeve 42. The block is adjustable by means of a hand screw 54 which can be locked in position 5 by a lock nut 56. The purpose of the bearing block is to force the driven sleeve against the plain half bearing 44 to reduce the oil film and thereby prevent appreciable deflection of the work holder due to the pressure 10 of the grinding wheel.

The sleeve 42 is driven by a worm wheel 60 meshing with a worm 62 on a worm shaft 64 journalled in the front and in the rear of the casing 48. The worm shaft is keyed 15 to a pulley 66 driven by a belt 68 from a small pulley 70 on the shaft of an electric motor 72 resting on the casing. The worm shaft is journalled at one end on a double row ball bearing 74 and at the other end on 20 a single row ball bearing 76 the outer race ring of which can slide in its supporting casing. Lubricant is supplied to the double row bearing through the inlet 78.

A small amount of oil from the worm 25 wheel casing is allowed to circulate through a plain bearing 44 by passing through a longitudinally extending passage 80 which is closed at the outer end by a ring 82 and a flanged ring 84, these being fastened by 30 screws to the casing and embracing a collar 86 on the sleeve 42. Suitable packing may be inserted between the rings. Bearing 44 terminates short of the ring 82. The half bearing 46 has an oil film take-up similar 35 to that of the bearing 44, being closed at the top and rear by a bearing cap 88 enclosing a bearing block 90 adjusted by a hand screw 92. Oil is allowed to circulate around the half bearing 46 by passing from the 40 worm wheel casing through a longitudinal groove 94.

The casing 48 has a shouldered recess at the left receiving an inner race ring 100, a central race ring 102, and an outer race 45 ring 104, rows of balls being interposed between the central race ring and the others. The central ring is supported on a flanged sleeve 106 fitting against a shoulder on the driven sleeve 42 and clamped by nuts 108 threaded on the end of the driven sleeve. The central ring 102 is clamped against the 50 flange of sleeve 106 by a ring 110 interposed between it and the nuts 108. The outer race ring 104 of the thrust bearing is held against axial movement by an annular flange 112 formed on a casing 114 attached by screws 116 to the casing 48. The sleeve 42 is thus supported for rotary movement by the plain bearings and is held against axial movement 55 by the thrust bearings. The sleeve is hollow and the bore is larger than the rod 22 to allow the latter to have easy sliding movement endwise.

The sleeve 42 has its bore enlarged at the 60 left to receive a shouldered sleeve 118 which

slidably supports the left end of the rod 22. A disc 122 is threaded on the sleeve 118 and fastened by a radial plug 124 having an abutting locking screw 126. A rectangular, rotatable yoke 128 surrounds the rod 22 and carries a couple of three armed levers 130 pivoted at 132 and each having a nose 134 engaging the disc 122 near the periphery. Each lever also has an inwardly extending arm 138, the nose of which engages the end 75 of a nut 140 threaded on the rod 22 and fastened by a set screw. The yoke 128 has its hub 142 supported on this nut. The long arms 144 of the three armed levers bear against a convex cam surface 146 on a slide- 80 able carrier 148 which is grooved at 150 to receive a split band 152 having oppositely extending pins 154 trunnioned in the arms of a fork 156 depending from and keyed to a rock shaft 160 journalled at 155 on the casing 114. The rock shaft is also journalled in the upper end of a bracket 162 having a lug 164 resting on a tongue 166 of the machine frame to which the bracket is bolted. A depending arm 168 keyed to the 90 rock shaft is connected by a link 170 to a hand lever 172 pivoted at 174 to the frame.

In operation, a bushing 12, loaded with work pieces, is slipped over the spindle 14. Then the clamping member 26 is slipped 95 over the shaft and the hand lever 172 is manipulated to draw the rod 22 to the left. This movement is effected through the cam and the three armed levers, the cam carrier 148 sliding to the left and forcing the arms 144 outwardly until they reach a locked position due to the contour of the cam. The outward movement of the arms 144 causes the levers to pivot and their inwardly extending arms 138 engage the nut 140 and slide the rod 22 to the left until the work pieces are firmly clamped against the shoulder 10. The bushing with its work pieces is released for replacement by another, previously loaded bushing, by moving the parts 105 in the reverse order.

Although the invention has been described by reference to a certain specific construction, it should be understood that, in its broader aspects, it is not necessarily limited thereto.

I claim:

1. In apparatus of the character described, a rotary cylindrical spindle for supporting a hollow work piece, a hollow cylindrical bushing sleeved on the spindle, said bushing being slidable off and on the spindle for loading, a limit device associated with the spindle, a quick detachable member engaging the limit device and contacting with the work piece to hold the latter on the spindle, means extending through the spindle for moving the limit device away from the work, and means for sliding the bushing on the spindle; substantially as described.

2. In apparatus of the character described, a rotary cylindrical spindle for supporting a hollow work piece, a hollow cylindrical bushing sleeved on the spindle and having a shoulder abutting the end of a work piece, said bushing being slidable off and on the spindle for loading, a movable limit device associated with the spindle, and a quick detachable member engaging the limit device and arranged to hold the work piece against said shoulder; substantially as described.
3. In apparatus of the character described, a rotary spindle, a hollow cylindrical bushing sleeved on the spindle for holding a plurality of hollow work pieces in axial alignment, said bushing being slidable off and on the spindle for loading, and means for removably holding the bushing with its work pieces on the spindle; substantially as described.
4. In apparatus of the class described, a rotary spindle, a plain cylindrical bushing sleeved on the spindle for supporting a plurality of hollow work pieces in axial alignment, said bushing being slidable off and on the spindle for loading, a member extending beyond the end of the bushing and supporting a limit device smaller than the bore of the work pieces, and a detachable U-shaped member insertable radially between the limit device and the endmost work piece; substantially as described.
5. In apparatus of the class described, a hollow spindle, a hollow cylindrical bushing sleeved on the spindle for supporting a plurality of hollow work pieces in axial alignment, said bushing being slidable off and on the spindle for loading and having a work abutting shoulder, a rod extending through the spindle, and means at the end of the rod to detachably hold the work pieces and the bushing on the spindle; substantially as described.
6. In apparatus of the character described, a hollow cylindrical spindle having means to enter and support a hollow work piece, and mechanism for clamping the work piece on the spindle, said mechanism comprising a rod keyed to the spindle, a member near the end of the rod to engage the work piece, leverage applying mechanism for moving the rod, and means operated by the rod to release the work piece from the spindle; substantially as described.
7. In apparatus of the character described, a rotary cylindrical spindle for entering and supporting a hollow work
- piece, a head on the spindle having openings parallel to its axis, pins slidable in the openings, a rod movable in line with the axis of the spindle, and a cross pin fixed on the rod to directly engage said slidable pins; substantially as described.
8. In apparatus of the character described, a hollow cylindrical spindle for supporting a hollow work piece, a head on the spindle having an opening parallel to its axis, a pin slidable in the opening, a rod slidable through the spindle and having means to clamp the work piece against the head, and means on the rod for directly engaging and sliding said pin; substantially as described.
9. In apparatus of the character described, a rotary spindle, a bushing sleeved on the spindle and supporting a hollow work piece, a pin slidable parallel to the axis of the spindle in line with the bushing, and means for sliding the pin to release the bushing; substantially as described.
10. In apparatus of the character described, a rotary spindle, a bushing sleeved on the spindle and supporting a hollow work piece, a pin slidable parallel to the axis of the spindle in line with the bushing, a driving lug on the bushing engaging said pin, and means for sliding the pin; substantially as described.
11. In apparatus of the character described, a rotary driven member and a loading sleeve for holding hollow work pieces, one of said members being inside the other, said loading sleeve being removable from the driven member for loading, by axial movement, and means for securing the loading sleeve to the driven member; substantially as described.
12. In apparatus of the character described, a hollow spindle having means to support a work piece, a driving sleeve connected to the spindle, a rod slidably keyed to the spindle and projecting at its ends through the spindle and through the sleeve, said rod having means at one end to engage and hold a work piece, a cam member supported and slidable on the other end of the rod, a disk and a yoke surrounding the rod, and levers pivoted on the yoke and engaging the disk and the cam member and having connection with the rod to slide the latter; substantially as described.

In testimony whereof I hereunto affix my signature.

WILLIAM H. CHAPMAN.
